COMBINATION BRIEF CASE AND TRAVELING BAG

Robert Gray, Philadelphia, Pa.

Application November 5, 1949, Serial No. 125,824

2 Claims. (Cl. 150—1.6)

1

This invention relates to a combination brief case and traveling bag, which is so constructed and arranged as to permit various parts thereof to be joined to each other to form different combinations according to the varying requirements of the user.

Professional men and the like are frequently required to make trips, involving different lengths of time, and also to carry with them papers in different quantities.

Heretofore the common practice, in connection with such trips, has been to carry the clothing required in one piece of luggage, and the papers in a separate brief case or the like. Persons who have been compelled to use such combinations of luggage and brief cases are quite familiar with the awkwardness and difficulties in carrying the same.

The principal object of the present invention is to provide a piece of luggage in which small quantities of clothing may be carried for short trips, such as those of an overnight, or slightly longer duration, and at the same time having provision for carrying such papers as are necessary in connection with the business of the trip.

With the foregoing object in view, the present invention contemplates the provision of a piece of luggage which, in its simplest arrangement, may comprise two parts, which may be joined to each other with separable fasteners, preferably of the slide operated type, which however can be extended in size to increase the capacity thereof by the interposition of gussets, which gussets are also provided with complementary separable fasteners so that the gussets may be inserted and secured between the side members easily and conveniently when desired.

The insertable gussets may be provided in various widths, and they may be used singly, or in combination, so that desired widths of the device may be obtained.

The invention further contemplates the provision of an internal partition which, if desired, may be utilized for the separation of papers from clothing, and said partition may also be so constructed and arranged as to receive papers or other things in a pocket or pockets formed therein.

The nature and characteristic features of the invention will be more readily understood from the following description, taken in connection with the accompanying drawings forming part hereof, in which:

Figure 1 is a perspective view of the parts arranged to form a brief case embodying certain

2

features of the present invention, the same being shown in its closed condition;

Fig. 2 is a perspective view of the brief case arrangement shown in Fig. 1, but with the same opened to permit access to the interior thereof;

Fig. 3 is a transverse section taken approximately on the line 3—3 of Fig. 1;

Fig. 4 is a view similar to Fig. 2, the same being shown with an intermediate sized gusset partially secured to the side portions by separable fasteners of the slide operated type, the parts being joined to provide a traveling bag;

Fig. 5 is a view similar to Fig. 1 of the traveling bag made up of the parts shown in Fig. 4, but with the same in closed condition;

Fig. 6 is a transverse section taken approximately on the line 6—6 of Fig. 5; and

Figs. 7 and 8 are fragmentary top views of portions of gussets of widths different from those shown in Figs. 4 and 5.

It should, of course, be understood that the description and drawings herein are illustrative merely, and that various modifications and changes may be made in the structure disclosed without departing from the spirit of the invention.

Referring to the drawings, the combination brief case and traveling bag there shown comprises essentially two side members 10 and 11 each having, on its inner face, a flap 12 extending entirely around said member, and said members are joined to each other by a separable fastener 13 of the slide operated type commonly known as "zippers."

Each of the side members 10 and 11 is provided with a carrying handle member 14 of any preferred type. By thus providing each of the side members 10 and 11 with a separate handle, said handles may be used together no matter if the side members only are used to form a brief case, or if one or more of the gussets are used therewith to form a travelling bag.

It will be noted by reference to Fig. 2 of the drawings that the two complementary parts of the separable fastener 13 extend entirely around the edges of the flaps 12 so that when the slide member 15 is slid around the flaps 12 of the side members 10 and 11 of the bag, the two parts will be secured to each other and the brief case thus provided will be closed on all four edges.

The arrangement is such, however, that by retracting the slide member 15 to the registering device 16, preferably located along the edges of the bottom flaps 12 of the side members 10 and

11, the two parts 10 and 11 of the structure may be completely separated from each other.

A partition member 17 is preferably mounted detachably on the interior face of the part 10 and the same may be secured to said part by snap fasteners 18. The partition member 17 is preferably provided with a front panel 19 to provide a pocket 20 on the partition member 17 which pocket may be closed by a strap 21 and buckle 22.

There is also provided in connection with the two side parts 10 and 11, of the brief case arrangement, a series of gussets 23, 24 and 25, one of said gussets 24, of intermediate width, being shown in Figs. 4 and 5 of the drawings; a portion of another gusset 25, of greater width being shown in Fig. 7, and a portion of still another gusset 23, of lesser width being shown in Fig. 8.

The gusset members 23, 24 and 25, preferably comprise elongated strips of flexible material, such as cloth, canvas, leather, or the like, having snap fasteners 26 at their respective ends for securing the ends to each other when the arrangement is as shown in Fig. 5 of the drawings.

Each of the gusset members 23, 24 and 25 is of such length as to extend entirely around the edges of the flaps 12 of the side members 10 and 11, and each of said gussets is provided, on each edge, with separable fastener members 13 adapted to coact with and to be joined to the complementary fastener members 13 provided on the flaps 12 of the side members 10 and 11 and, also, joinable to the similar separable fastener members of the other gussets.

The gusset members 23, 24 and 25 may also be provided with tabs 30 each carrying portions of snap fasteners 18 for the purpose of securing the partition member 17 to whichever of said gussets may be in use, and thus separate the interior of the bag into separate compartments so that the clothing needed for a trip of a night or two, may be placed on one side of the partition, and the papers used in connection with the trip may be placed on the other side thereof.

The pocket provided in the partition member 17 may be used for any desired purpose, but preferably would be employed for carrying the folded gusset strips 23, 24 and 25 of the size or sizes which are not being used upon a particular occasion, so that the same will always be available at any time it may be necessary to increase the size of the bag.

It will, of course, be readily apparent that the gussets 23, 24 and 25 may be selectively used, and any two or more may be simultaneously used, to change the capacity of the bag whenever it may become necessary or desirable to do so.

I claim:

1. A combination brief case and travelling bag comprising a pair of substantially similar side members each having projecting flaps extending entirely around adjacent the edges of said side members and each having a separate handle extending beyond the upper edge thereof, slide operated separable fastener devices extending entirely around the edges of said flaps adapted to join said side members to each other to form a brief case, and a gusset made of flexible material and adapted to be inserted between the side members to increase the capacity of the device and thereby form a travelling bag, said gusset having slide operated separable fasteners on each edge thereof complementary to and adapted to engage the separable fasteners carried by the flaps of the side members thereby to secure the gusset between the side members.
2. A combination brief case and travelling bag comprising a pair of substantially similar side members each having slide operated separable fastener devices carried thereby and extending entirely around adjacent the edges thereof and adapted to detachably secure said side members to each other and thereby form a brief case, each of said side members having a separate handle extending beyond the upper edge thereof, a gusset made of flexible material and adapted to be inserted between the side members to increase the capacity of the device and thereby form a travelling bag, said gusset having slide operated separable fasteners on the edges thereof complementary to and adapted to engage the separable fasteners carried by the side members thereby to secure said gusset between the side members, a partition member, and means for mounting said partition in the interior of the device and for detachably securing the same to portions of the gusset.

ROBERT GRAY.
